G. L. KOLLOCK AND R. P. MARTIN.

AUTOMATIC HAMMER.

APPLICATION FILED NOV. 9, 1917.

1,310,575.

Patented July 22, 1919.

INVENTORS:

George L. Kollock
Robert P. Martin.

BY
E. H. Beattley
their ATTORNEY.

UNITED STATES PATENT OFFICE.

GEORGE L. KOLLOCK AND ROBERT P. MARTIN, OF SEATTLE, WASHINGTON, ASSIGNEES
TO UNIVERSAL HAMMER COMPANY, OF SEATTLE, WASHINGTON, A CORPORATION
OF WASHINGTON.

AUTOMATIC HAMMER.

1,310,575.

Specification of Letters Patent. Patented July 22, 1919.

Application filed November 9, 1917. Serial No. 201,148.

To all whom it may concern:

Be it known that we, GEORGE L. KOLLOCK, a citizen of the United States, residing at Seattle, in the county of King and State of Washington, and ROBERT P. MARTIN, a citizen of the United States, residing at Seattle, in the county of King and State of Washington, have invented certain new and useful Improvements in Automatic Hammers, the following being a full, clear, and exact disclosure of the one form of our invention which we at present deem preferable.

For a detailed description of the present form of our invention, reference may be had to the following specification and to the accompanying drawing, which shows a longitudinal section of our device.

Our invention relates to an automatic hammer wherein the hammer element or striker is actuated by a spring and the spring is periodically tensioned and released by a rotary motor.

Our present device is also of the kind in which a hollow or annular cam is employed and our invention relates chiefly to the means for utilizing the cam to alternately tension and release the spring.

Referring to the drawing, A represents one part of a cylindrical two-part casing, the other, or second part of said casing being represented at B. Within the first part of the casing is an electric-motor armature having its shaft extending longitudinally of the casing. The field-magnet of the motor is formed by the steel of the casing on the inside of which are the inwardly projecting poles surrounded by the exciting coils C.

At the upper end is secured a handle D and a cap-plate E closes the end of the casing and carries one of the bearings for the armature. The part A has a screw-joint connection with the part B. In the latter part is a striker F, housing a squared portion F¹ passing through a squared opening in the transverse disk G, which disk is seated against a shoulder in the casing. A spring H encircles the shaft of the striker, bearing at one end against a washer J, screwed on the striker and at the other end against the aforesaid disk G. Obviously if the spring is under compression it will tend to drive the striker downward against the anvil or tool K. An annular cam L is secured to the upper end of the striker; it includes a plurality of spiral bearing surfaces (three being indi-

cated in the drawing) each terminating in a saw-tooth point. The cam is inclosed within a drum M which rotates on the disk G with intervening balls or rollers. Inside of drum M are rollers O, which are journaled on the drum and bear against the spiral surfaces of the cam. As the drum rotates, the rollers, acting on the cam-surfaces, lift the striker against the force of spring H and when they reach the saw-tooth points the striker and spring are released and a blow produced on the tool K. The drum has also a downwardly projecting central stud N which enters a socket in the upper end of the striker and aids in guiding it. The drum is also provided with a short spindle which projects upward through the flanged disk R and carries a driving gear wheel P⁴, that meshes with a pinion P³ on the shaft of gear wheel P² that is driven by pinion P¹ on the motor shaft. The shaft which carries gear wheel P² and pinion P³ is journaled in the disk R and the disk V, which latter also contains the lower bearing of the motor shaft. A fan G on the motor shaft provides for ventilation and cooling.

What we claim as new and desire to secure by Letters Patent is:

1. An automatic hammer comprising a reciprocating striker, an actuating spring therefor, an annular cam for the striker, a cam-operating member engaging the cam, said cam and said operating member being concentric to said striker, and an electric motor for driving the said member. 90

2. An automatic hammer comprising a reciprocating striker, an actuating spring therefor, a spring-tensioning cam secured to the striker, an operating member concentric to said striker and engaging the cam and an electric motor for driving the said member. 95

3. An automatic hammer comprising a reciprocating striker, an actuating spring therefor, an annular spring-tensioning cam secured to the striker, an operating member outside of said cam but extending inwardly to engage the cam, said cam and said operating member being concentric to said striker, and an electric motor for driving said member. 105

4. An automatic hammer comprising a reciprocating striker, an actuating spring therefor, a spring-tensioning cam concentric with the striker, a cam-actuating member 110

- 2
- outside of the cam but extending inwardly to engage the cam with a clearance space above the cam, and a motor-driven shaft concentric with the cam and driving the 5 said member.
5. An automatic hammer comprising a reciprocating striker, an actuating spring therefor, an annular spring-tensioning cam concentric with the striker and secured thereto with its working cam-surface on the 10 under side, a cam-operating member engaging said cam-surface and provided with a depending part outside of said cam, and an electric motor for operating said member.
15. An automatic hammer comprising a reciprocating striker, an actuating spring therefor, a spring-tensioning cam, a cam-operating member inclosing said cam and an electric motor having its shaft in line with 20 the striker and geared to the said member.
7. An automatic hammer comprising a reciprocating striker, an actuating spring therefor, an annular spring-tensioning cam
- secured to the striker, an operating member inclosing the cam and engaging its under 25 side with a central guide thereon for the striker, and a driving motor for said member.
8. An automatic hammer comprising a reciprocating striker, an actuating spring 30 therefor, a spring-tensioning cam, an operating member, an electric motor having its shaft in line with the axis of said member, and a countershaft geared to said member and also to the motor shaft. 35
9. An automatic hammer comprising a hammer casing, a reciprocating striker, an actuating spring therefor, an operating member provided with rollers bearing on 40 said cam, a seat for said member in the hammer casing with intermediate rolling bearings and an electric motor for driving said member. 45

Signed this 23rd day of October, 1917.

GEORGE L. KOLLOCK.
ROBERT P. MARTIN.
